ATTORNEY.

UNITED STATES PATENT OFFICE.

GEORGE W. RICHARDSON, OF CHICAGO, ILLINOIS, ASSIGNOR OF ONE-HALF
TO JASON H. SHEPARD, OF SAME PLACE.

DUMP-WAGON.

SPECIFICATION forming part of Letters Patent No. 377,331, dated January 31, 1888.

Application filed October 20, 1887. Serial No. 252,874. (No model.)

To all whom it may concern:

Be it known that I, GEORGE W. RICHARDSON, a citizen of the United States, and a resident of Chicago, county of Cook, State of Illinois, have invented new and useful Improvements in Dump-Wagons, of which the following is a specification, reference being had to the accompanying drawings, illustrating the invention, in which—

10 Figure 1 is a side elevation of a dump-wagon in which my invention is embodied; Fig. 2, a top or plan view of Fig. 1 with the wheels removed; Fig. 3, an end elevation of Figs. 1 and 2, looking in the direction indicated by dart Z; Fig. 4, a front elevation of Fig. 2, looking in the direction indicated by dart Y; Fig. 5, an enlarged view of one of the rings which hold the operating-levers in place.

15 This invention will be fully understood from the following description.

A A represent the sides, B the rear end, and C the front end, of the box.

20 d, Figs. 1, 2, and 4, is a fixed bottom in front of the box, and g g are side-boards to it, one of which is removed at Fig. 1, more clearly to show the parts.

25 D represents a shaft, which is preferably of hollow iron, extending longitudinally and centrally through the bottom box and over the fixed bottom d, and it is held in position by a metal collar, X, at each end, and to the front end of the shaft D is affixed a plate, b, and to the plate are affixed two levers, c c, and 30 to the under side of the shaft D are affixed stiff downwardly-projecting prongs V V V W, for the purpose of elevating the dump-bottoms G m, the prong W being curved, that it may be out of the way of the front 35 wheel, U. The dump-bottoms G are hinged to the shaft D at E, and the bottoms m, on the opposite side of the shaft, are hinged to it at F, as shown at Figs. 2 and 3. A rod, I, lying inside and close to the bottom of both 40 side-boards A A, has bearings in the end-board B C, so that it may be turned by an upwardly-projecting end-part, e. The sides of the rods I are provided with pins a a a, &c.,

to support the free edges of the dump-bottoms m G. The links f, Figs. 1, 2, 4, and 5, 50 are put over the upward-projecting parts e of the rods I, to hold the pins a level.

At Figs. 2 and 3 the bottoms G are represented as resting on the pins a, and the bottoms m are shown to be swung down as when 55 a load is to be dumped. The bottoms G m are allowed to fall down by removing the rings f, which will, by the weight of the load on the bottoms, bring the projecting parts e in positions shown by dotted lines p, Fig. 4, 60 and the pins will project downward. The bottoms are elevated by turning the levers c c, so as to bring the prongs V W to horizontal positions, and the bottoms are then locked by turning the parts e e to vertical positions and securing them by the links f f. The reason for the two levers c is to have 65 one lever at all times in convenient position for use.

It is necessary in this kind of a wagon to 70 have the bottom of the box well up from the axle-trees, for generally small wheels, T U, are employed, and also to have the box strongly supported.

N is the rear axle-tree, and L is the bolster, between which and the axle-tree is placed the lower portion, M, of a bar of iron, which extends up on and is fastened to each side of the box, as shown at J J, and passing over the bolster L, at each end, is a strap of iron, 80 O, which, by nuts and bolts K, is secured to a brace, Q S, whose top ends are secured to the box A. By this means the axle-tree bolster and box attachment is sufficiently strong to support the great weight required in hauling broken stone and coal, and at a proper height for the box to clear its dumped load. The forward bolster is secured by a similar support, O K, to the turn-table i n, which gives to the forward connection suitable 85 strength.

I claim and desire to secure by Letters Patent—

1. In dumping-wagons, the box A B C, combined with the longitudinal central shaft, 95 D, with the hinged bottoms G m, the shaft

provided with the prongs V W, in combination with the levers c c, for elevating the bottoms, as specified.

2. The shaft D, provided with the prongs V W and levers c c, in combination with box A B C, the bottoms G m, the shafts i e, provided with the pins a, and the links f, as specified.

3. The box A B C, bottoms G m, rod D,

elevated bolster L, the plates M J, and braces to S Q, substantially as and for the purpose specified.

October 13, 1887.

GEORGE W. RICHARDSON.
